CLAIM

The ornamental design for a case for a mobile device, as shown and described.

DESCRIPTION

FIG. 1 is a front perspective view showing a first embodiment of our new design for a case for a mobile device.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view showing a second embodiment of our new design for a case for a mobile device

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front perspective view showing a third embodiment of our new design for a case for a mobile device

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The dash-dash broken lines illustrate portions of the case for mobile device that form no part of the claimed design. The dot-dash broken lines represent symbolic break lines, and

(Continued)

form no part of the claimed design. The case for mobile device is shown with a symbolic break in its length. The appearance of any portion of the article between the break lines forms no part of the claimed design.
